[57] CLAIM

The ornamental design for a tire, as shown and described.

DESCRIPTION

FIG. 1 is a perspective view of a tire showing my new design, it being understood that the tread design is repeated throughout the circumference of the tire as shown schematically by solid lines, the opposite side being substantially the same as that shown;

FIG. 2 is an inverted plan view thereof; and
FIG. 3 is a side elevational view thereof.

FIG. 1.

FIG. 2.

FIG. 3.
